UNITED STATES PATENT OFFICE.

HAROLD I. STAGE, OF DENVER, COLORADO.

ROCK-DRILL SEATING AND CONTROLLING MEANS.

1,336,930.

Specification of Letters Patent. Patented Apr. 13, 1920.

Application filed August 15, 1918. Serial No. 250,038.

To all whom it may concern:

Be it known that I, HAROLD I. STAGE, a citizen of the United States, residing at Denver, in the city and county of Denver 5 and State of Colorado, have invented new and useful Improvements in Rock-Drill Seating and Controlling Means, of which the following is a specification.

This invention relates to certain new and 10 useful improvements in rock drill seating and controlling means and has for one of its principal objects to provide means for admitting live air to cushion and balance the drill feeding mechanism.

15 A further object is to provide an improved machine in which air pressure is employed to effect absolute seating of the drill in the bottom of the hole to eliminate reciprocation of the drill and prevent cutting 20 or breaking away of the corners of the drill.

Another object resides in a live air cushion for the drill in the feeding thereof, so as to effect an automatic feed simulating the firm but yieldable pressure of the manual feed.

25 Further, the invention resides in the features of construction and the arrangements and combinations of parts described in detail in the following specification and defined in a succinct manner in the appended 30 claims, reference being had to the accompanying drawings wherein—

Figure 1 is a side elevation of the improved drill machine constituting the subject matter of the present invention;

35 Fig. 2 is a top plan view thereof;

Fig. 3 is a fragmentary longitudinal section through the drill-carrying end of the working or hammer cylinder;

40 Fig. 4 is a transverse section on line 4—4 of Fig. 3;

Fig. 5 is a longitudinal section through the feeding mechanism;

Fig. 6 is a fragmentary horizontal section on line 6—6 of Fig. 5;

45 Fig. 7 is a transverse section on line 7—7 of Fig. 6;

Figs. 8 and 9 are similar sections on lines 8—8 and 9—9 of Fig. 5;

50 Fig. 10 is a sectional view similar to Fig. 9 showing a different position of the valve; and

Fig. 11 is a vertical longitudinal section through the forward head of the feed cylinder.

55 Referring more in detail to the draw-

ings, the numeral 1 designates the power cylinder in which is arranged the impact motor hammer 2 for operating on the drill bit 3. At the front head of the machine, a sleeve 4 is chambered to receive the hammer and has a reduced forward socket in which the bit is retained. A spacing ring 5 abuts the inner end of the sleeve and seats in the inner end of a multi-chamber cylindrical member 6, which conformably receives the sleeve 4 and has an internal shoulder 7 against which the latter seats. Surrounding the cylindrical member 6 is the front head or cap 8 having its front wall perforated to receive the collar 9 that is fixedly carried by the bit 3. The rear end of the cap 8 has outstanding perforated ears 10 alined with like ears 11, extending from the valve 6, for receiving the tie rods 12.

The forward end of the cylindrical member 6 is formed with an annular series of piston cylinders 13 that extend longitudinally of the member and communicate at their inner ends through radial ports 14 with a peripheral groove 15, this groove receiving fluid under pressure from a pipe 16 that is screwed into the head over a port 17. One of the cylinders 13, preferably the one diametrically opposite port 17, is formed with a second port 18, which communicates 85 through a second head port 19 with the pipe 20, which delivers the fluid to the drill feeding mechanism. In each cylinder a piston 21 is slidably mounted one of which opens and closes the port 18 and thus controls the flow of the live fluid. A drill seating control ring 22 connects the outer ends of the pistons and between this ring and the front wall of head 8 is disposed a floating ring 23 for engagement with the collar 9 of the bit. 95

From any suitable source, fluid pressure is conducted by pipe 24 to the valve head 25, which controls the admission of fluid to the power cylinder 1 for reciprocating the hammer 2, a valve 26 being interposed in the 100 pipe for shutting off the supply to the valve head, if it is so desired. Branching from pipe 24 is the pipe 16, for conducting live air to the drill holding means which, by reason of the cushioning effect of the compressed air, causes absolute seating of the drill on the bottom of the hole, thereby 105 eliminating reciprocation of the drill and preventing cutting or breaking away of the corners thereof.

The drill feed mechanism comprises a cylinder 27 which has its rear end closed by a head 28 and its forward end closed by a head 29. The head 29 has a supporting disk 30 by which the machine is mounted on a suitable support, not shown. The head 29 receives a clamping ring 31 which clamps a packing ring 32 therein to provide a stuffing box construction for the tubular piston rod casing 33. This casing carries on its outer or forward end a sleeve 34 having a bracket extension 35 that embraces the cylinder of the impact motor, being securely connected thereto by the bolts 36.

15 The heads of cylinder 27 are connected by tie rods or bolts 37 and upon these bolts is slidably a bracket support 38 having a forwardly extending arm terminating in an upstanding plate 39. This plate is perforated to receive the tie rods 12 that project through the adjacent head 40 of cylinder 1. Between the nuts 41, on the rods 12, and the plate 39 are coiled springs 42 normally holding the latter against the cylinder head 25 and designed to ease the operation and rebound of the machine.

30 The piston 43, which is operable in cylinder 27, has a tubular piston rod 44 arranged concentrically in the casing 33 and formed at its forward end into a valve casing 45 that is seated in the sleeve 34, as illustrated in Fig. 5. The protruding end of this valve casing is threaded for receiving a cap nut 46. The inner end of the piston rod casing is 35 enlarged and shaped to securely clamp and hold the piston packing 47 between it and the piston 43.

40 A rack or toothed member 48 is disposed within the hollow piston rod, being supported therefrom at its forward end by a spider 49, secured to said member, and receiving support at its rear end from a feeding device 50 which is connected thereto. This device has its stem slidably carried by 45 the cylinder head 28, being resiliently urged forward by the coiled spring 51. The rack tube 48 is provided on its outer opposite sides with a series of teeth or notches 52, those on one side being preferably staggered 50 relative to those on the opposite side thereof. A pair of pawls 53 are pivotally carried by the piston 43 for engaging the teeth 52 so that as the piston and its connected drill are advanced the pawls by engaging with 55 the teeth will prevent retrograde movement. A U-shaped spring 54, secured between its ends to the piston 43, has its terminals bearing on the pawls to urge them to operative position.

60 A valve 55 is rotatably seated in the valve casing 45 and carries a key rod 56 which extends through the piston rod and the spider 49 into the tubular rack member. This key rod is square in cross section and 65 while it is relatively movable in an axial

manner to the spider the latter may readily be rotated upon turning the rod. Consequently, the teeth 52 may be turned out of engagement with the pawl to permit the piston being retracted.

70 Fluid pressure is admitted from pipe 20 through the thimble connection 57 (Figs. 9 and 10) and into the valve casing 45, the latter being formed with connecting passageways or by-passes 58 for connecting the ports of the valve 55 and also embodying a duct 59 leading to the space between the piston rod and its casing. The valve is provided with an inlet port 60 communicating with the duct 59 and an inlet port 61 establishing communication with the space within the piston rod. Both inlet ports also serve as exhaust ports when connected by the passageways 58 with the radial exhaust ports 62 and 63 which merge into 85 a common port 64 leading axially through the valve stem and handle 65. A coiled spring 66 encircles the valve stem and urges a tight seating of the valve, at the same time allowing rotation thereof.

90 In operation, assuming that the drill has just been set and started in its operation upon a rock barrier. The impact motor hammer 2 will drive the drill forwardly, sliding it in its supporting sleeve until the 95 collar 9 has been carried outwardly a fixed distance at which time the piston 21 will have uncovered port 18, the drill seating control ring following the said collar by the live air pressure acting against the 100 piston 21.

As soon as port 18 is uncovered, live air pressure is admitted into cylinder 27 until the port 18 is again closed by the piston 21. This closing of the port 18 results from the 105 advancing of the drilling machine while the drill itself has been held comparatively still by seating or engaging on the bottom of the hole being drilled. The machine is in a constant state of reciprocation caused by impact 110 of the hammer against the drill and the spring 51 will accordingly be constantly compressed and will upon expansion, and with the aid of the air pressure, back of piston 43, feed the latter forward upon full 115 stroking of the hammer. The air pressure back of the piston 43 acts as a balance for the impact motor and all of the parts carried by the latter. Thus as the motor moved forward more live air is admitted 120 back of the piston 43 and the latter thus is at all times balanced by air pressure.

Consequently, the drill is intermittently fed and at the same time is held against its work by the control ring which is constantly 125 held in abutting relation with the collar 9 by the fluid pressure. Thus in addition to the automatic advance of the machine, the control ring holds the drill firmly against the bottom of the hole at all times while 130

drilling, which overcomes and eliminates the rebound or reciprocatory movement of the drill which accompanies the loosely held drill and breaking of or wear on the corners 5 of the latter, heretofore employed in drilling machines.

After the drilling has ceased and it is desired to return the machine to normal position for another start, the valve is adjusted 10 to permit the ingress of fluid pressure in advance of the piston 43 to reverse the travel thereof, the rack or toothed member 48 being simultaneously rotated from engagement by the pawls 53 so that the return of the machine to starting position is 15 easily and expeditiously performed.

The piston rod casing is provided in its inner end with the ports 67, whereby the air pressure, that is admitted to the space 20 between the piston rod and its casing, may find a way of escape into the cylinder 27 in advance of the piston to act thereon in returning the mechanism.

The fluid pressure while holding the drill 25 constantly on the work, performs this function in a manner similar to the manual feed which heretofore has been the only practical feed as the hand pressure permits sufficient yieldability and flexibility to prevent 30 chipping or cutting of the drill and at the same time eliminating the rebound of the drill.

What is claimed is:

1. In a drill feeding machine, a cylinder, 35 an impact motor hammer therein, a drill, a sleeve supporting the latter, a head for the cylinder, through which the drill extends, a ring encircling the drill and arranged within the head for limited movement to 40 hold the drill against its work, and pneumatic means for operating the ring.

2. In a drill feeding machine, a cylinder, an impact motor hammer therein, a drill, a sleeve supporting the latter, a head for the 45 cylinder through which the drill extends, a ring encircling the drill and arranged within the head for limited movement to hold the drill against its work, a cylinder within the head, a piston operable 50 therein to move the ring to operative position, and means for sliding the piston in the second cylinder.

3. In a drill feeding machine, a cylinder, an impact motor hammer therein, a drill, 55 a sleeve supporting the latter, a head for the cylinder through which the drill extends, a ring encircling the drill and arranged within the head for limited movement to hold the drill against its work, a 60 collar fixed on the drill against which the ring abuts, and fluid pressure means yieldably urging the ring forwardly.

4. In a drill feeding machine, a cylinder, an impact motor hammer therein, a drill, a 65 sleeve supporting the latter, a head for the

cylinder through which the drill extends, a ring encircling the drill and arranged within the head for limited movement to hold the drill against its work, a plurality of chambers, means for supplying air pressure thereto, and pistons operable in the plural chambers for moving the ring forwardly.

5. In a drill feeding machine, a cylinder, an impact motor hammer therein, a drill, 75 a sleeve supporting the latter, a head for the cylinder through which the drill extends, a ring encircling the drill and arranged within the head for limited movement to hold the drill against its work, a 80 multi-chambered member arranged within the head about the sleeve, the chambers of said member opening forwardly, and pistons in the chambers of said member connected to the ring.

6. In a drill feeding machine, a cylinder, an impact motor hammer therein, a drill, a sleeve supporting the latter, a head for the cylinder through which the drill extends, a ring encircling the drill and arranged within the head for limited movement to hold the drill against its work, a multi-chambered member arranged within the head about the sleeve, the chambers of 90 said member opening forwardly and having 95 radial ports leading from their rear ends, said member also having a peripheral groove connecting the ports, and pistons operable in the chambers of said member to move the ring forwardly.

7. In a drill feeding machine, a cylinder, an impact motor hammer therein, a drill, a sleeve supporting the latter, a head for the cylinder through which the drill extends, a ring encircling the drill and arranged within the head for limited movement to hold the drill against its work, a multi-chambered member arranged within the head about the sleeve, the chambers of said member opening forwardly and having radial ports leading 100 from their rear ends, said member also having a peripheral groove connecting the ports, pistons operable in the chambers of 105 said member to move the ring forwardly, and a fluid pressure inlet in the head communicating with the groove of the member.

8. In a drill feeding machine, a cylinder, an impact motor hammer therein, a drill, a sleeve supporting the latter, a head for the cylinder through which the drill extends, a 110 ring encircling the drill and arranged within the head for limited movement to hold the drill against its work, a multi-chambered member arranged within the head about the sleeve, the chambers of said member opening forwardly and having radial ports leading 115 from their rear ends, said member also having a peripheral groove connecting the ports, pistons operable in the chambers of said member to move the ring forwardly, 120 and a fluid pressure inlet in the head communicating with the groove of the member.

125

- and a fluid pressure inlet in the head communicating with the groove of the member, one chamber of the latter having an outlet port which is opened and closed by the contained piston for controlling the fluid pressure to operative parts of the machine.
9. In a drill feeding machine, a drill, an impact motor carrying the same, and a feed mechanism for the drill comprising a cylinder, a hollow piston head reciprocal in the cylinder and having a hollow piston rod terminating in a valve casing, a valve in the latter for controlling the admission of fluid pressure through the piston rod into the cylinder, means connecting the motor to the piston rod for simultaneous movement, and a casing surrounding the piston rod and communicating at its inner end with the cylinder in advance of the piston head, said valve casing having a port controlled by said valve and leading to the space between the piston rod and its inclosing casing, said piston rod casing having a port establishing communication between said space and the interior of the cylinder in advance of the hollow piston head.
10. In a drill feeding machine, a drill, an impact motor carrying the same, and a feed mechanism for the drill comprising a cylinder, a hollow piston head reciprocal in the cylinder and having a hollow piston rod terminating in a valve casing, a valve in the latter for controlling the admission of fluid pressure through the piston rod into the cylinder, means for locking the piston step by step, and means operable by the valve for rendering the locking means inoperative.
11. In a drill feeding machine, a drill, an impact motor carrying the same, and a feed mechanism for the drill comprising a cylinder, a hollow piston head reciprocal in the cylinder and having a hollow piston rod terminating in a valve casing, a valve in the latter for controlling the admission of fluid pressure through the piston rod into the cylinder, a toothed member in the cylinder, a pawl carried by the piston and engaging the toothed member to hold the piston head against returning, and means connecting the piston rod to the motor.
12. In a drill feeding machine, a drill, an impact motor carrying the same, and a feed mechanism for the drill comprising a cylinder, a hollow piston head reciprocal in the cylinder and having a hollow piston rod terminating in a valve casing, a valve in the latter for controlling the admission of fluid pressure through the piston rod into the cylinder, means supporting the motor from the piston rod, a rotatable toothed member telescopically related to the piston head and disposed in the cylinder, a pawl carried by the piston head for engaging the teeth of the toothed member, and means for rotat-

ing the tooth member to bring its teeth from engagement by the pawl to permit return movement of the piston head.

13. In a drill feeding machine, a drill, an impact motor carrying the same, and a feed mechanism for the drill comprising a cylinder, a hollow piston head reciprocal in the cylinder and having a hollow piston rod terminating in a valve casing, a valve in the latter for controlling the admission of fluid pressure through the piston rod into the cylinder, means for supporting the motor from the piston rod, a rotatable toothed member telescopically related to the piston head and disposed in the cylinder, a pawl carried by the piston head for engaging the teeth of the toothed member, and a key rod operable by the valve and slidably connected to the toothed member to rotate the latter and thereby disengage its teeth from the pawl.

14. In a drill feeding machine, a drill, an impact motor carrying the same, and a feed mechanism for the drill comprising a cylinder, a hollow piston head reciprocal in the cylinder and having a hollow piston rod terminating in a valve casing, a valve in the latter for controlling the admission of fluid pressure through the piston rod into the cylinder, means supporting the motor from the piston rod, a rotatable toothed member telescopically related to the piston head and disposed in the cylinder, a pawl carried by the piston head for engaging the teeth of the toothed member, a key rod operable by the valve and slidably connected to the toothed member to rotate the latter and thereby disengage its teeth from the pawl, and a device secured to the inner end of the toothed member and yieldably and slidably connected to the adjacent head of the cylinder.

15. In a drill feeding machine, a drill, an impact motor carrying the same, and a feed mechanism for the drill comprising a cylinder, a piston head operable in the cylinder having an outwardly extending piston rod on its inner end, a bracket member connecting the outer end of the piston rod to the motor, packing seating on the piston head, and a sleeve-like casing for the piston head interposed between the bracket member and packing for holding the latter seated.

16. In a drill feeding machine, an impact motor including a sleeve, a multi-chambered member inclosing the latter the chambers of said member opening forwardly and communicating one with another, a piston in each chamber, a drill seating control member operable by the said pistons, a drill feeding mechanism including a feeding piston, means supporting the motor from the said feeding piston, and means for admitting fluid pressure to the feeding mechanism and controlled by one of the first pistons.

17. In a drill feeding machine, a cylinder, an impact motor hammer therein, a drill, a sleeve supporting the latter, a head for the cylinder through which the drill extends, a ring encircling the drill and arranged within the head for limited movement to hold the drill against its work, a multi-chambered member arranged within the head about the sleeve, the chambers of said member opening 5 forwardly and having radial ports leading from their rear ends, said member also having a peripheral groove connecting the ports, pistons operable in the chambers of said member to move the ring forwardly, a fluid pressure inlet in the head communicating with the groove of the member, one chamber of the latter having an outlet port which is opened and closed by the contained piston, and a fluid-operated drill feeding 10 mechanism connected to the outer port of said member.
18. In a drill feeding machine, a cylinder, an impact motor hammer therein, a drill, a sleeve supporting the latter, a head for the cylinder through which the drill extends, a ring encircling the drill and arranged within the head for limited movement to hold the drill against its work, a multi-chambered member arranged within the head about the sleeve, the chambers of said member opening 15 forwardly and having radial ports leading from their rear ends, said member also having a peripheral groove connecting the ports, pistons operable in the chambers of said member to move the ring forwardly, a fluid pressure inlet in the head communicating with the groove of the member, one chamber of the latter having an outlet port which is opened and closed by the contained piston, and a fluid-operated drill feeding 20 mechanism including a cylinder and piston, means connecting the latter to the first named cylinder, and means for admitting fluid pressure from the outlet port of said member to 25 the feeding mechanism cylinder.
19. In a drill feeding machine, a cylinder, an impact motor hammer therein, a drill, a sleeve supporting the latter, a head for the cylinder through which the drill extends, a ring encircling the drill and arranged within the head for limited movement to hold the drill against its work, a cylinder within the head having a fluid pressure inlet and outlet, means operable in the second cylinder to move the ring to operative position and for 30 opening and closing the outlet, and a feed mechanism for the drill comprising a cylinder, and a fluid cushioned piston reciprocal in the latter and connected to the first cylinder, said feed mechanism being connected 35 to the said outlet port.
20. In a drill feeding machine, a cylinder, an impact motor hammer therein, a drill, a sleeve supporting the latter, a head for the cylinder through which the drill extends, a ring encircling the drill and arranged within the head for limited movement to hold the drill against its work, a cylinder within the head having a fluid pressure inlet and outlet, means operable in the second cylinder to move the ring to operative position and for 40 opening and closing the outlet, and a feed mechanism for the drill comprising a cylinder, a hollow piston head reciprocal in the cylinder and having a hollow piston rod 45 terminating in a valve casing, a valve in the latter for controlling the admission of fluid pressure through the piston rod into the cylinder, means supporting the first cylinder from the hollow piston rod, and means connecting the outlet of the second cylinder to 50 the valve.
- In testimony whereof I have hereunto set my hand in the presence of two subscribing witnesses.
